UNITED STATES PATENT OFFICE.

FREDERICK C. HERBERMANN, OF MOUNT VERNON, NEW YORK.

DESIGN FOR A COMBINED CLOCK AND SUPPORT THEREFOR.

Application filed January 14, 1928. Serial No. 24,878. Term of patent 3½ years.

To all whom it may concern:

Be it known that I, FREDERICK C. HERBERMANN, a citizen of the United States, residing at Mount Vernon, in the county of Westchester and State of New York, have invented a new, original, and ornamental Design for a Combined Clock and Support Therefor, of which the following is a specification, reference being had to the accompanying drawing, forming part thereof.

Fig. 1 is a front view of a combined clock

and support therefor showing my new design.

Fig. 2 is a side view thereof.

I claim:

The ornamental design for a combined clock and support therefor, as shown.

In witness whereof I have hereunto set my hand at New York, county of New York, State of New York, this 12th day of January, 1928.

FREDERICK C. HERBERMANN.
